PLASTER RETAINING STRUCTURE

Roy Phillips, Dallas, Tex.

Application March 7, 1938, Serial No. 194,406
Renewed July 12, 1939

5 Claims. (Cl. 72—118)

This invention relates to devices for supporting plaster coating such as those used in building construction and has particular reference to a lathing tie for securing furring material, and consequently the plaster, in place.

The primary object of the invention is to provide a simplified construction of a tie for "floating" or crack proof walls that is economical in its manufacture.

10 Another object of the invention is to provide a tie of this character which can be adapted to the various conventional furring elements known to the trade, such as metal lathing and wall construction board.

15 A further object of the invention resides in the provision of a tie for securing furring elements and plaster coating to a wall or ceiling in such a manner as to allow the surface to shift relative to its supports when caused to move by contraction and expansion due to variations in temperature or by reason of settling caused by faulty foundations, thus minimizing the cracking of the plaster.

20 Yet another object of the invention resides in the provision of a device of this character which minimizes the transmission of sound through partitioning surfaces.

25 Broadly, the invention seeks to provide a tie for securing furring elements to supports which is of economical construction as well as being readily adaptable to the conventional lathing materials, and in the provision of a furring tie which is capable of reducing the transmission of sound prevalent in conventional wall construction.

30 With the foregoing objects as paramount, other and lesser objects will become manifest as the description proceeds taken in connection with the appended drawing wherein:

35 Figure 1 is a perspective view of two wall studs illustrating fragmentary portions of wall board attached thereto by the employment of the invention.

40 Figure 2 is an elevational view of a stud particularly illustrating the positions of the ties at the intersections between the boards.

45 Figure 3 is a perspective view of a stud supporting a fragment of metal lath by use of the invention when the employment of wall board is not desired.

50 Figure 4 is a perspective view of one form of the invention wherein the clasp is slidably engaged in the body member.

55 Figure 5 is a perspective view of another form of the invention illustrating the clasp integral with its body member.

Figure 6 is a perspective view of the form of the invention illustrated in Figure 4 illustrating the sound insulation material applied thereto.

Figure 7 is a perspective view of the form of the invention illustrated in Figure 5 with the sound insulating material applied and showing the clasp engaging a fragmentary portion of metal lathing, and

Figure 8 is a plan view of several of the ties applied to a strip of felt or similar material.

Continuing with a more detailed description of the drawing, the numeral 1 designates studs to which the plaster surface is to be applied, and to which, in conventional practice, lathing or wall board is nailed. By the employment of 15 the present invention, the furring surface may be applied in such a manner as to provide what is known to the art as a floating wall, that is the plastered surface is capable of vertical and horizontal movement occasioned by changes of temperature of the settling or shifting of the framework of the building.

20 The present invention is comprised of a body member 2 which is substantially rectangular in shape and relatively thin and has a longitudinal slot 3 arranged therethrough which, in manufacture, may be stamped out. The resulting piece of material is formed into a laterally projecting clasp 4 and is to be bent over a bar or bars 5 of metal lathing, as illustrated in Figures 1, 2, 3 25 and 7, for securing the furring element.

25 In one form of the invention, as illustrated in Figures 4 and 6, the clasp 4 is entirely severed from the slot 3 and is formed in such a manner as to have projecting lugs 6 at each end thereof and is bent at its center a so that the resulting thickness is of a lesser dimension than the width of the slot 3. The lugs 6 are bent outwardly and the entire clasp is then inserted through the slot 3, thus providing a slidably connection between the clasp 4 and the body 2, the point a, when applied to lath, or bent, prevents the said slot from becoming disengaged from the said body.

30 In the form of the invention illustrated in Figures 5 and 7, the clasp 4 is partially stamped and extends from the body 2, one end of the clasp remaining integral therewith.

35 A nail 7, having a relatively large head 8, slidably engages the slot 3 and is, in application, driven into the stud 1. Thus, when the clasp 4 40 is attached to metal lathing, the plaster surface (not shown) is rotatably and slidably secured to the supporting stud 1.

45 The body member 2 is covered with insulating medium 9, as illustrated in Figures 6 and 7, such 50

as felt or fibrous paper, and in the form of the invention illustrated in Figures 4 and 6, prevents the free movement, or frangible engagement, of the clasp 4 in the slot 3. Another strip of flexible material 10 which also may be a non-conductor of sound, is disposed around the body 2 and the medium 9 for securing the nail head 8 in place. Thus when the medium 9 and the material 10 are thus fashioned and secured, individual units are prepared and ready for use.

The invention is particularly adaptable for securing wall board 11 to studs 1. The body 2 is first secured to the stud 1 by driving the nail 7 therein and by placing the edges b of the wall board 11 against the clasp 4 of the device and thence by applying small squares or rectangles of lathing 5, as illustrated in Figure 1, over the clasp 4 and by then bending the point a of the said clasp. This operation necessitates only the use of an ordinary hammer.

With particular reference to Figure 1, sections of rectangular wall board 11 are applied in staggered formation. Thus, by reason of the rotatable and slidable connection of the clasp 4 with the body members 2, the nailing of the individual units need not necessarily be in perfect alignment with the board edges b, but the clasps 4 may be turned and positioned so as to engage the edges of the wall board 11, as particularly illustrated in Figure 2.

When applying metal lathing 6 instead of wall board, it is preferred that a strip of felt 12 or the like be positioned between the body 2 and the stud 1, as illustrated in Figure 3, for sound insulation, the same being secured by units of the invention, that is the nail 7 is driven through the said felt and the clasp 4 is bent over and secured to the lathing 6. The plaster can then be applied to the lathing 5 and move in any direction within the plane of the plastered surface, the same as in the described construction employing wall board.

As illustrated in Figure 8, the flexible material 10, in addition to its application as described, may also enclose a strip of building paper 13 or similar material whereby the units of the invention may be conveniently handled when being applied to studs or the like.

Manifestly, the structure shown is capable of considerable changes and modifications from time to time by those skilled in the art and such changes and modifications as may be resorted to falling within the spirit and intent of the in-

vention may also be considered as falling within the scope of the appended claims.

What is claimed is:

1. A furring element to be secured to supports comprising a body member, a clasp extending from the said body member for attachment with a base element, means for slidably securing the said body member to the said support, and sound insulating means arranged between the said supports, the said body member, and the said engaging means. 5

2. A furring element to be secured to supports comprising a body member, a clasp extending from the said body member for attachment with a base element, means slidably and pivotally securing the said body member to the said support and sound insulating means between the said supports, the said body member, and the said engaging means. 15

3. In a furring element for pivotally and slidably securing base elements to supports, a body member having a longitudinal slot arranged therethrough, a clasp extending from the said body member for engaging the said base element, means extending through the said slot for securing the said body to the said support, and insulation material between the said body member and the said support. 20 25

4. A furring element for pivotally and slidably securing base elements to supports, comprising a relatively flat body member, a longitudinal slot in the said body, a clasp extending laterally from the said slot for securing the said base element, a nail slidably engaging the said slot for securing the said body to the said support, sound insulating material between the head of the said nail and the said body and between the said body and the said support, and means frangibly retaining the said nail in the said slot before securing said nail to said support. 30 35 40

5. A furring element for pivotally and slidably securing base elements to supports, including a relatively flat body member, a longitudinal slot in the said body, a clasp extending laterally from the said slot for securing the said base element, a nail slidably engaging the said slot for securing the said body to the said support, sound insulating material between the head of the said nail and the said body, said insulating material providing means for frangibly retaining the said nail in the said slot, and means attaching a series of the said furring elements to a strip of flexible material. 45 50

ROY PHILLIPS.
